US0D1065075S

(12) **United States Design Patent** (10) **Patent No.:** **US D1,065,075 S**
(45) **Date of Patent:** **** Mar. 4, 2025**

(54) **COMBINATION TABLE AND CHARGER**

(71) Applicant: **eMoMo Technology Co., Ltd.**,
Shenzhen (CN)

(72) Inventors: **Dasheng Hu**, Dao (CN); **Wei Zhou**,
Wuhan (CN); **Zaigui Yang**, Xiushan (CN);
Wenji Tang, Shenzhen (CN);
Jing Song, Shenzhen (CN); **Yushu Zhao**, Shenzhen (CN); **Juntao Chen**, Shenzhen (CN)

(73) Assignee: **eMoMo Technology Co., Ltd.**,
Shenzhen (CN)

(**) Term: **15 Years**

(21) Appl. No.: **29/849,978**

(22) Filed: **Aug. 16, 2022**

(30) **Foreign Application Priority Data**

Apr. 1, 2022 (CN) 202230180196.2

(51) **LOC (15) Cl.** **13-02**

(52) **U.S. Cl.**

USPC **D13/108**; D13/162

(57) **CLAIM**

The ornamental design for a combination table and charger as shown and described.

DESCRIPTION

FIG. 1 is a front, right, top perspective view of a combination table and charger showing our new design;

FIG. 2 is a front, left, bottom perspective view of the combination table and charger of FIG. 1

FIG. 3 is a top plan view of the combination table and charger of FIG. 1;

FIG. 4 is a bottom plan view of the combination table and charger of FIG. 1;

FIG. 5 is a right-side elevated view of the combination table and charger of FIG. 1;

FIG. 6 is a left-side elevated view of the combination table and charger of FIG. 1;

FIG. 7 is a front elevated view of the combination table and charger of FIG. 1; and,

FIG. 8 is a rear elevated view of the combination table and charger of FIG. 1.

The broken lines consisting of dashes show portions of the combination table and charger that form no part of the claimed design.

1 Claim, 8 Drawing Sheets
